COMPUTING DEVICE

William Farbman, New York, N. Y.

Application April 5, 1947, Serial No. 739,676

8 Claims. (Cl. 235—74)

1

This invention relates to computing devices and more particularly to an adding machine or the like, of the type that may be carried about in a pocket such as of a vest or coat, etc.

One of the objects of this invention is to provide such an adding machine which is extremely small in size, thin, light weight, and economical to manufacture. The device is constructed of a minimum of parts, and a series of numbering wheels is provided each of which actuates a succeeding wheel so as to eliminate transmission gears or like components.

Another object of this invention is to provide a series of numbering wheels arranged to perform operations of addition, multiplication or division and wherein each wheel directly actuates a succeeding wheel and is arranged to effectively by-pass a preceding wheel without interfering therewith. This objective is accomplished, moreover, by a minimum of component parts insuring cheapness of manufacture as well as ease of operation.

Still another object of this invention is to provide a numbering wheel for such an adding machine which is constructed of a substantially single component but which is so formed as to form multiple functions. Thus, the numbering wheel incorporates not only a driving member, but gear teeth and actuating openings as well.

Other objects of my invention will be apparent from the following description, it being understood that the above general statements of the objects of my invention are intended to describe and not limit it in any manner.

Referring to the drawings:

Fig. 1 is a top plan view of a miniature adding machine or the like constructed pursuant to the instant invention.

Fig. 2 is a view similar to Fig. 1 with the top cover removed.

Fig. 3 is a rear view of the device with the bottom cover removed.

Fig. 4 is a cross section taken along the lines 4—4 of Fig. 1.

The device comprises a case having the top cover 10 and the bottom cover 11 which telescope to form an enclosure for the numbering wheels. In order to maintain the assembly of the case, there is provided a series of studs 12 which are enlarged at 12a and 12b adjacent the faces of the respective top and bottom covers. Studs 12 have other functions as will be herein-after understood in that they serve as shafts for the numbering wheels and further insure the proper spacing between the top and bottom covers on the one hand and between the numbering wheels and the bottom cover on the other hand.

2

Rotatably mounted on the studs are the numbering wheels 15, 16, 17, 18, 19 and 20. Wheel 15 represents the units wheel or column, wheel 16 represents the tens, wheels 17 represents the hundreds, and so forth to the last wheel 20. It is to be understood, of course, that many more or less wheels may be added depending upon the desired capacity of the device.

Wheel 15, as are the other wheels, is formed of a one piece disc of metallic material or the like having a central opening to receive stud 12 and is further formed with a laterally projecting driving arm 21 which is a planar continuation of the disc surface. Radially punched out inwardly from the circumference 22 of wheel 15 is a series of teeth 23 which are integral with wheel 15 in that they are struck downwardly, therefrom, as, by a suitable die. Teeth 23 are preferably, but not necessarily, formed arcuately, as illustrated in Fig. 4 so that they do not extend exactly perpendicularly to the surface of wheel 15 but they curve slightly toward the circumference 22. It is further to be noted that the striking down of teeth 23 forms holes 24 which make possible the direct or primary actuation of the wheels by means of a pointed instrument applied selectively therein and without requiring any additions to the wheel.

Referring to Fig. 2, it will be seen that each wheel underlaps a succeeding wheel while it overlaps or passes over the face of a preceding wheel. The terms "underlap" and "overlap" must, of course, depend upon the position of the device, since an overlap becomes an underlap when the device is reversed. When the wheels are mounted on the studs, they are rotatable thereon, so that when a stylus is applied to one of the holes 24 and revolved, the wheel is rotated on the stud for a distance depending upon the particular hole 24 in which the stylus was inserted. As will be hereinafter described, the teeth and driving arms are so arranged that the driving arm of a preceding wheel will engage but one tooth of a succeeding wheel in any complete revolution of the preceding wheel so as to transmit one step to each succeeding wheel.

In order to hold any wheel to a set position each time it is actuated, spring clips 30 are wound around studs 31 and are formed with projections 32 and 33 adapted to engage adjacent teeth of the wheels and to produce "clicks" as the wheels are turned. Thus, if a wheel is turned only sufficiently to cause the spring to traverse a tooth, it will click between the next two teeth and insure the proper setting of the wheel, the arc of each tooth preventing disengagement of the spring.

Referring to Fig. 3, it will be observed that the driving arm 21 describes a circle partially represented by the dotted arc 35 which cuts across the succeeding wheel 16. The teeth 23a of wheel 16 have their bases arranged along a circle partially represented by the arc 36. It will be appreciated, therefore, that the arm 21 only makes driving contact with one tooth of the succeeding wheel and it avoids actuating either tooth adjacent thereto. This will move wheel 16 one digit and the number series 38 embodying the numbers 0-9 which are stamped on the top side of the wheel adjacent to the circumference 22 will be increased one digit when doing an addition, to show an increase of one digit in the answer. The proper number will then be observed by the user in the opening 37a formed in the cover 10 of the device. In like manner, a reverse movement of the driving arm 21, as when performing subtraction or division, will show as a decrease by one digit of the succeeding wheel.

The units wheel has the driving arm centered between the sixth and seventh driving holes 24 so that it is adjacent the number 7 of the number series 38.

The driving arm 21a of the wheel 16 is disposed adjacent to the number 2 of its number series 38. This results because of the fact that the wheels turn each other directly so that a clockwise motion of a driving wheel produces a counterclockwise movement of the succeeding wheel. The number series 38 on each wheel is further arranged in reverse order, that of wheel 15 running from 1 through zero, while that of wheel 16 runs reversely from zero to 1. Thus, when wheel 16 is turned a sufficient number of digits to bring its arm 21a across wheel 15, it will pass over wheel 15 so as to avoid the teeth 23. The arm 21a, therefore, can only actuate wheel 17 through its teeth 23b and can in no way produce a movement of the wheel 15. The action of the device is thus unidirectional and progressive in a forward direction.

The overlapping disposition of the wheels is illustrated in the enlarged cross section of Fig. 4 although it will be understood that in the completed device the tilted arrangement of each wheel is not noticeable. The wheels are of thin sheet metal or the like so that to all appearances all the wheels are on a single plane. In order to maintain the teeth of each wheel spaced from the floor of the bottom cover, the studs 12 are formed with bosses 12c which rotatably support the wheels.

The top cover 10 of the device has arcuate slots 40 formed therein through which the openings 24 are rendered accessible. The closed portion of the slots serves as stop means for a stylus, as will be hereinafter described. Associated with each wheel are two sets of numerals running from 0-9, but in opposite directions. The inner radius set 41 is used in addition and multiplication functions while the outer radius set 42 is used for subtraction and division functions. An arrow 43 appearing centrally of each numeral set 41 indicates the direction that the wheel should be turned for the addition and multiplication functions.

The adding machine is operated as follows:

The operator will insert a pointed stylus into a desired opening 24 appearing through the slot 40 so that he may actuate the wheel 15. It is first desirable that all the wheels be "cleared" so that all the answer openings 37 will show

zeros. Assume now that it is desired to perform the following addition:

5

784
962
677
—

Answer=2423

10 The stylus will be inserted in the opening adjacent the number 7 in the hundreds column represented by the wheel 17. For purposes of better illustration, the particular opening is designated in Fig. 1 by the numeral 24b. The 15 stylus will then be forced around the arcuate slot 40b until the stylus strikes the point S of slot 40b serving as the stop means. In this manner, wheel 17 will have been turned the equivalent of seven digits and the number 7 of the number series 38 will appear in the answer opening 37b. The number 8 is then turned in the direction of the arrow in the tens column as represented by the wheel 16. The number 8 will then appear in the answer opening 37a. 20 The same operation is performed for the units column in respect to the number 4 and the number 4 will then appear in the answer opening 37. At this point, the answer spaces will show 784. Then the stylus is inserted into the opening adjacent the number 9 in the inner series 30 of the hundreds column and the direction of the arrow is followed until the stylus strikes the stop S. This operation will be continued for the numbers 6 and 2 in the tens and units column respectively. At this point, the answer spaces 35 will show 1746 which is an accumulation of the two quantities thus far added. The number 677 is then applied in the same manner, following the direction of the arrows and the sum total 40 2423 will be seen in the answer openings.

For the function of subtraction, assume the problem

45

732
—426
306

The machine is first cleared to show zeros in the answer openings. First the numbers 732 are 50 placed in the hundreds, tens and units columns respectively in the same manner as for the addition heretofore described and following the direction of the arrows. At this point, the answer openings show 732. It is then necessary to subtract 426 from the total. For such subtraction, the outer radius numerals 42 are used, and the direction of the movement is opposite to that shown by the arrows. Thus, a stylus is inserted in the opening adjacent the outer numeral 4 and 55 the wheel is rotated until the stylus strikes the end S1 of the slot 40b. In this manner, 4 is reduced from the hundreds column, similarly 2 is thereafter reduced from the tens column, and 6 is reduced from the units column. At this point, 60 the answer 306 appears in the answer openings 65 etc.

For the function of multiplication, assume the problem of

70

257
46
—
1542
1028
—
11822

75

First clearing the machine, the number 257 is added six times in the device. This is accomplished by repeating the placing of number 2 in the hundreds column for six successive times, repeating the number 5 in the tens column for six successive times and then repeating the number 7 in the units column for six successive times. At this point, 1542 appears in the answer openings since it is the sum total of 257 six times. Next, 257 is multiplied by 4. However, just as in normal multiplication operations, the next figures are all moved one space to the left. Therefore, on the adding machine, we repeat the number 2 on the thousands column four successive times, then the number 5 in the hundreds column four successive times, then the number 7 in the tens column four successive times. At this point, the total 11822 appears in the answer spaces.

For the function of division, assume the problem of

46

257/11822
1028
1542
1542

After clearing the machine, we place

1 in the ten-thousands column,
1 in the thousands column,
3 in the hundreds column,
2 in the tens column,
2 in the units column.

The inner radius numerals are used and the direction of the arrows is followed. Division is, however, a subtraction function so that for the next operation the outer radius numerals are used and the direction of the movement is opposite to that shown by the arrows. Now, in looking at the answer space from right to left, the first group of numbers higher than 257, the divisor, is 1182. We then reduce 2 from the thousands column, 5 from the hundreds column and 7 from the tens column, at which point we find the number 925 in the answer space. Thereafter, we keep reducing 257 in the same way until after the fourth time we find the answer space number shows 154. This figure 4 is then written down or remembered as this number is the first one of the answer of quotient. Now, as required in subtraction, we move one space to the right and keep subtracting 257 from the figure 1542 appearing in the answer openings until the total in such answer openings is less than 257. Accordingly, we reduce 2 from the hundreds column, 5 from the tens column and 7 from the units column and continue this procedure until the answer spaces all show zeros. This requires six such reductions and our quotient is, therefore, 46.

It can be seen from the foregoing that an adding machine has been produced which consists essentially of wheels only, formed to produce such multiple functions as to dispense with many conventional components. Each driving arm rotates a succeeding wheel the equivalent of one digit after making a complete revolution. It will be appreciated, therefore, that at some times, a single movement of the first wheel will be transmitted to every succeeding wheel as when the answer column of the device is changing from 99,999 to 100,000. In this instance, every driving arm save the last actuates a succeeding wheel.

While there has been described what at pres-

ent is considered a preferred embodiment of the invention, it will be evident that many changes and modifications may be made therein without departing from its spirit.

5 I claim:

1. A computing device comprising a support, a series of planar, numbered wheels respectively representing units, tens, hundreds and so forth, rotatably mounted on said support, each of said wheels being arranged in overlapping relationship with adjacent wheels, a driving arm integrally formed on each of said wheels and laterally extending therefrom and in substantially the same plane thereof and so as to overlap adjacent wheels, each of said wheels having struck-out teeth formed on the surfaces thereof and so as to be engaged by the driving arm of a preceding wheel, said teeth and driving arms being arranged to prevent engagement of the teeth of one wheel by the driving arm of a rotating succeeding wheel, said struck-out teeth forming externally accessible surface openings in said wheels whereby said wheels may be driven through primary actuation utilizing said openings.

2. A computing device according to claim 1 and wherein said means to prevent engagement comprises the arrangement of said wheels so as to underlap a succeeding wheel while overlapping a preceding wheel so that the driving arms pass under succeeding wheels and pass over preceding wheels, said teeth being formed in a radial pattern on the undersides of the wheels to produce engagement thereof by a driving arm of a preceding wheel.

3. A computing device according to claim 2 and wherein said teeth are spaced inwardly from the periphery of a wheel while the driving arms are formed outwardly whereby the teeth describe a circle of smaller diameter than the driving arms, the driving arm being thereby operative to cut across the underside of a succeeding wheel so as to engage only one tooth thereof while avoiding teeth adjacent to said one tooth.

4. A computing device comprising a support, a series of planar, numbered and externally visible computing wheels each rotatably mounted in lateral relationship on said support and arranged for successive inter-actuation, a plurality of teeth on each of said wheels, a driving arm integral with each wheel and on substantially the same plane therewith for engaging teeth of a succeeding wheel so as to produce said inter-actuation, said driving arms being arranged to pass by the teeth of a preceding wheel without actuating the preceding wheel whereby a continuous and direct drive may be established among said series of wheels in a forward direction, said teeth being formed on the undersides of the wheels and said wheels being mutually arranged in overlapping relationship so that said driving arms pass over the faces of preceding wheels and on the undersides of succeeding wheels, said driving arms extending laterally from each wheel.

5. A computing device comprising a support, a series of planar, numbered and externally visible computing wheels each rotatably mounted in lateral relationship on said support and arranged for successive inter-actuation, a plurality of teeth on each of said wheels, a driving arm integral with each wheel and on substantially the same plane therewith for engaging teeth of a succeeding wheel so as to produce said inter-actuation, said driving arms being arranged to pass by the teeth of a preceding wheel without actuating the preceding wheel whereby a continuous and direct

drive may be established among said series of wheels in a forward direction, said teeth being integral with the wheels and struck-out downwardly therefrom, said driving arms extending laterally from each wheel.

6. A computing device according to claim 5 wherein said teeth are struck-out downwardly from the undersides of the wheels and said driving arms pass over said undersides of succeeding wheels and over the faces of preceding wheels. 10

7. A computing device according to claim 5 and wherein said struck-out teeth form upper surface and externally accessible openings in the wheels whereby each wheel may be physically actuated by a pointed instrument inserted into one 15 of its openings.

8. In a computing device, the sub-combination of a planar computing wheel, said wheel comprising a series of radially arranged teeth struck-out downwardly from the wheel so as to simultaneously form said teeth and wheel actuating open- 20

ings corresponding thereto, and a driving arm laterally disposed on the wheel and integral therewith, said teeth being arranged inwardly of the periphery of said wheel and said arm being arranged outwardly thereof.
